United States Patent Office.

WILLIAM WEBSTER, OF ROCHESTER, NEW YORK.

Design No. 2,559, dated January 15, 1867.

DESIGN FOR A FLOWER GARDEN.

The Schedule referred to in these Letters Patent and making part of the same.

TO ALL WHOM IT MAY CONCERN:

Be it known that I, WILLIAM WEBSTER, of the city of Rochester, and county of Monroe, and State of New York, have originated a new Design for Garden Flower Beds, and which I name the title as follows, viz, the American Style of Flower Gardens, of which the following is a full and exact description, reference being had to the accompanying drawings, making part of this specification.

To enable others skilled in gardening to use my invention, I will proceed to describe the operation.

I construct my beds according to mathematical rules, and either sow seeds, plant bulbs, or flowering plants in them, in strips, in such a way as to produce the colors shown in the drawing, or by massing in such forms as to produce those results.

What I claim as my invention, and desire to secure by Letters Patent, is—

The design for an ornamental flower bed as herein set forth and shown.
